UNITED STATES PATENT OFFICE

CHARLES HENRI DANNEQUIN, OF LIVRY-GARGAN, FRANCE

APPARATUS FOR PRODUCING DENTAL ANÆSTHESIA

Application filed February 25, 1931, Serial No. 518,284, and in France March 1, 1930.

My invention relates to apparatus used for producing dental anæsthesia by progressive refrigeration, either through emission of air refrigerated by carbonic acid, or by means of ethyl chloride in the form of a jet.

Apparatus of this kind, which have been used up to now in surgical dentistry are often difficult to manipulate. Besides, in order that such apparatus may have a satisfactory analgesic effect and in order that all risk of mortification of the pulp may be avoided, it is necessary that the refrigeration should be absolutely progressive.

The apparatus according to my invention fulfills this condition.

The appended drawing shows the construction of the apparatus, considered in the case when ethyl chloride is being used as refrigerating agent, for example. The apparatus could be used just as well for anæsthetizing by means of other volatile liquids. Instead of delivering the refrigerating agent in the form of a jet of liquid, it ensures its previous gasification and diffusion in a draught of air directed onto the tooth being treated. Moreover, it is easy to manipulate and takes up little room.

A preferred embodiment of my invention, given by way of example, is illustrated in the appended drawing in which:

Fig. 1 shows the whole of the apparatus;

Fig. 2 is an axial section of the instrument which is used to diffuse the refrigerating agent in the air and to direct the gaseous refrigerating mixture onto the part being anæsthetized;

Fig. 3 is a vertical section, taken at right angles to the preceding one;

Figs. 4 and 5 are two cross sections on the lines A—A and B—B of Figs. 2 and 3 respectively.

Adverting to Fig. 1 it is seen that the device comprises the diffusing instrument A, a bottle B containing the ethyl chloride and, for the producing of the stream of air at low pressure, a small turbine C, driven by a motor D.

The draught of air provided by the turbine is brought to the diffusing instrument through a flexible rubber tube 1, around

which is wound a fine metallic tube 2, which connects the bottle B to said instrument.

As the accessories B, C, D, may be fixed in a suitable place in the room, the operator holding in his hand the instrument A, keeps the full liberty of his movements.

The gasifying and diffusing instrument A, which is the principal object of my invention, comprises a closed casing 3, through the end 4 of which, pass the tubes 1 and 2. 60 These, after traversing a solid piece 5, open into a first diffusion chamber 6, above which is provided a second rather long tubular chamber 7, the part 6—7 being screwed onto the piece 5 in order to allow of the instrument being easily taken to pieces.

The end part of tube 2, through which passes the ethyl chloride, merely consists of a small canal 8 made in the piece 5, and prolonged by a capillary conduit 9, of a small 70 nozzle 10. Said nozzle when the instrument is not in use, is closed by a small metallic stopper 11, supported by a rotary rod 12, controlled by a small lever 13 which the operator pushes in an oblique slot 14. A spring 75 15 pushes the rod and the obturating stopper towards the bottom of the instrument. The direction of the displacement to be given to the lever 13 in slot 14 in order to open the capillary tube 9, is shown by arrow f of Fig. 3. 80

An interesting character of the instrument lies in the fact that the working of lever 12 which allows the ingress of the refrigerating agent into chambers 6 and 7 causes, simultaneously, the shutting off of a contact 16 on the 85 feeding circuit 17 of motor C. The result is that the turbine begins to give out the necessary air for the diffusion of the ethyl chloride at the same moment when said ethyl chloride begins to fill the diffusion chambers. 90

It has been noted that the intimate mixture of the ethyl chloride with the air is only imperfectly made when the chambers are empty. It has been found that on the contrary, a total diffusion of the anæsthetic agent 95 in the air is obtained by filling tube 7 with cotton wool, ends of wool, fibers of asbestos, etc.... still better by stuffing the chimney with a strand of amadou 18. The use of this stuffing, is an important part of my invention. 100

The mixture is sent onto the part being treated by a small spout 19 screwed onto the end of tube 7. This spout is provided with slots 20, which prevent its clogging.

5 Lastly, the instrument may be advantageously finished by a guard tube 21 which is applied at its base over casing 3. This guard and casing 3 separate the cheek of the patient and the hand of the operator from the cold tube 7. An aperture in this outward guard 10 tube allows the operator to appreciate the temperature which is obtained, according to the aspect and thickness of the rime which is formed on said tube 7.

15 After use, it is necessary to be able to change the gasifying chambers 6 and 7, on whose walls a thick layer of rime has been formed which puts them temporarily out of use. To allow the easy removing and replacing of these chambers, the whole of 6 and 7 20 is made part of the guard tube 21, in any suitable manner, such as welds 24. In these conditions, by working on said tube, the gasifying chambers are easily unscrewed from the solid piece 5.

25 To isolate the casing 3 from the inside of the instrument, a groove 25 may be formed in piece 5, or else said piece may be provided with fins.

30 The guard tube is provided with a sliding bracket 22 supporting a mirror 23, which makes it easier to examine the region being anaesthetized.

35 The apparatus according to my invention might also be applied to general anaesthesia.

While I have disclosed what I deem to be the preferred embodiment of my device I do not wish to be limited thereto as there might be changes made in the construction, disposition and form of the parts without departing from the spirit of my invention as comprehended within the scope of the appended claims.

What I claim is:

45 1. An apparatus for producing dental anaesthesia through progressive refrigeration by a stream of air mixed with a refrigerating agent, which comprises in combination, a casing, a chamber in said casing, a capillary tube opening into said chamber, a bottle containing the refrigerating agent connected to said capillary tube, a second tube opening into said chamber, a turbine for feeding a stream of air into said last mentioned tube, a motor 50 for driving said turbine, means for simultaneously obturating said capillary tube and stopping said motor, an elongated tubular chamber opening into said first mentioned chamber, means in said tubular chamber for thoroughly completing the intimate mixture 55 of the air from the turbine with the refrigerating agent, and a nozzle at the end of said tubular chamber for directing the jet of the mixture onto the part to be anaesthetized.

60 2. An apparatus for producing dental an-

esthesia through progressive refrigeration by a stream of air mixed with a refrigerating agent, which comprises in combination, a casing, a chamber in said casing, a capillary tube opening into said chamber, a bottle containing the refrigerating agent connected to said capillary tube, a second tube opening into said chamber, a turbine for feeding a stream of air into said last mentioned tube, a motor for driving said turbine, means for simultaneously obturating said capillary tube and stopping said motor, an elongated tubular chamber communicating with said first mentioned chamber, a spongy material filling said tubular chamber for completing the intimate mixture of the refrigerating agent with air and a nozzle at the end of said tubular chamber for directing the jet of the mixture onto the part to be anaesthetized.

65 3. An apparatus for producing dental anaesthesia through progressive refrigeration by a stream of air mixed with a refrigerating agent, which comprises in combination, a casing, a chamber in said casing, a capillary tube opening into said chamber, a bottle containing the refrigerating agent connected to said capillary tube, a second tube opening into said chamber, a turbine for feeding a stream of air into said last mentioned tube, a motor for driving said turbine, means for simultaneously obturating said capillary tube and stopping said motor, an elongated tubular chamber opening into said first mentioned chamber, a strand of amadou stuffed inside 70 the tubular chamber for completing the intimate mixture of the refrigerating agent with air, and a nozzle at the end of said tubular chamber for directing the jet of the mixture onto the part to be anaesthetized.

75 4. An apparatus for producing dental anaesthesia through progressive refrigeration by a stream of air mixed with refrigerating agent, which comprises in combination, a casing, a chamber in said casing, a capillary tube opening into said chamber, a bottle containing the refrigerating agent connected to said capillary tube, a second tube opening into said chamber, a turbine for feeding a stream of air into said last mentioned tube, a motor for driving said turbine, a stopper adapted 80 to be applied against the end of said capillary tube, a lever for actuating said stopper, an electric contact operated by said lever for closing the feed circuit of said motor when the stopper is not on the obturating tube and opening it when the stopper is applied against the obturating tube, an elongated tubular chamber opening into said first mentioned chamber, a strand of amadou stuffed inside 85 the tubular chamber for completing the intimate mixture of the refrigerating agent with air, and a nozzle at the end of said tubular chamber for directing the jet of the mixture onto the part being anaesthetized.

90 5. An apparatus for producing dental an-
